United States Patent Office

Des. 203,190

Patented Dec. 14, 1965

203,190

EMBLEMATIC KEY OR SIMILAR ARTICLE

James C. Eaves, 557 Culpepper Road, Lexington, Ky.

Filed Apr. 21, 1964, Ser. No. 79,635

Term of patent 14 years

(Cl. D29—6)

FIGURE 1 is a front elevational view of the emblematic key or similar article embodying my new design.

FIGURE 2 is a sectional view taken on line 2—2 of FIGURE 1.

The back face of the emblematic key, opposite to the face shown in FIGURE 1, is plain and unornamented.

I claim:

The ornamental design for an emblematic key or similar article, substantially as shown and described.
